INVENTOR
George W. Duchemin.
BY
Mr. H. Campfield.
ATTORNEY

UNITED STATES PATENT OFFICE.

GEORGE W. DUCHEMIN, OF NEWARK, NEW JERSEY.

MACHINE FOR FINISHING THE ENDS OF TURNED ARTICLES.

Application filed June 13, 1922. Serial No. 568,066.

To all whom it may concern:

Be it known that I, GEORGE W. DUCHEMIN, a British subject, and a resident of Newark, county of Essex, and State of New Jersey, have invented certain new and useful Improvements in Machines for Finishing the Ends of Turned Articles, of which the following is a specification.

This invention relates to a machine for finishing the ends of turned articles, such as lasts, propellers and other articles which, in the original turning, have been supported at their ends, and the machine is designed to hold the article and also hold the pattern and turn them so that the pattern bears against the pattern wheel and a cutter bears against the last so that the ends are finished.

The machine is designed to provide a means whereby the pattern and the work in rotating chucks are rotated on axes which are perpendicular to axis on which the group of chucks is revolved.

The invention further consists in certain details of construction which will be hereinafter more fully described and finally embodied in the claims.

A machine carrying out my invention is illustrated in the accompanying drawings, in which Figure 1 is a front view of the machine with the cutters and pattern wheel retreated and the chucks turned to show the ends thereof. Figure 1^a is a detail top view of part of the means for rotating the chuck support. Figure 2 is a section on line 2—2 in Figure 1, but with the chucks turned to a position where the pattern wheel and the cutters bear against the pattern and the lasts. Figures 3 and 4 are diagrammatic top views showing gates holding the cutters and the chucks holding the lasts at the beginning and end of the cutting operation. Figure 5 is an elevation, partly in section, of the central part of the machine while the cutting is going on. Figure 6 is a similar view illustrating how the pattern and the lasts are initially aligned in the machine. Figure 7 is a perspective view of a frame which supports the swinging gates holding the cutters and pattern. Figure 8 is a detail of part of a clutch used in the machine. Figure 9 is a diagrammatic view showing the direction of rotation of the pattern and the two lasts. Figure 10 is an end view of a chuck used in the machine. Figure 11 is a similar view with the easing shown in section and the last removed. Figure 12 is a section taken on a

plane indicated by the line 12—12 in Figure 10, and Figure 13 is a perspective view of a gage plate used on the chuck.

The machine comprises a frame formed of a bed 10 consisting of legs on which the bottom rail 11 and the top rail 12 are supported, and frames 13 slide in the upper edge of the bottom rail 11 and the lower edge of the top rail 12 and are moved back and forth by handles 14, which, as will be seen from Figure 7, have their shafts 15 provided with pinions 16, and the racks 17 on the frames are in mesh with the pinions, so that as the handles 14 are turned the frames are moved together or apart, as desired, and while I show two frames in this machine, since I prefer to finish both ends of the work at the same time, it will be evident that only one can be employed and successively used on the two ends of the work.

Gates 18 are arranged to swing in the frames 13, one swinging to the rear and one swinging to the front, and are provided with pattern wheels, the one to the left in Figure 1 having a pattern wheel 19 which is idle, and having cutters 20 which are positively driven by means of the belts 21, shaft 22 and belt 23 which passes over the drum 25 on the main shaft 26 which receives its power through the pulley 27 driven by the belt 28. This is one form of driving mechanism for the cutter. Another form is illustrated to the right in Figure 1, in which the cutters 29 have their respective shafts 30 driven by belts 31 operated by the motor 32 carried on one of the arms of the gates. Latches 33 act by gravity to hold the gates in their outward position when the cutting operation is completed, as will be clearly seen from Figures 3 and 4.

Between the frames, and substantially in line therewith, is arranged a rotatable support 34 which receives a set of chucks 35, each chuck being opposite a pair of cutters and being adapted to hold either a pattern or the work, such as an unfinished last, so as to leave its ends exposed, as will be seen from Figures 2 and 5. These chucks 35, the details of which will be described hereinafter, hold the pattern and the lasts at substantially the center and are rotatable since the support 34 is rotatable, being mounted to rotate in the bearing 36 at the top and in the bearing 37 at the bottom, being adapted to either normally swing free so as to be freely rotated, or to be placed in positive

connection with the device to rotate it slowly so that the work is pressed against the cutters held in the gates.

Such friction device, shown at the top 5 of Figure 1, comprises a friction pulley 38 and a driving friction pulley 39 which is normally held just out of contact with it by reason of the carriage 40 in which it is mounted being held back by the screw 41, 10 the carriage 40 acting as a bearing for the worm gear 42 mounted on the same shaft as the driving friction pulley 39 and driven by a worm 43 on the shaft 44, driven by belts 45 and 46 from the jack shaft 47 which 15 is operated by the belt 48 from the main shaft 26. Each of the chucks is provided with a gear, the top one having the gear 49, which is in mesh with the gear 50, which gear is driven from the gear 51 in 20 the extension 52 of the casing of the chuck, the gear 51 also being in mesh with the gear 53 of the bottom chuck, but the gears 50 and 53 are not in mesh because, as will be seen from Figure 2, they are off-set 25 on different sides and thus operate in different planes, but are both in mesh with the gear 51, which provides for the direction of rotation of the chucks, as shown in Figure 9, the center one at *a* being the 30 pattern, the upper one at *b* and the lower one at *c* being the lasts, one of these, such as the lower one, operating in the same direction as the pattern, and the upper one at *b* operating in the opposite direction, 35 so that a pair of lasts, that is, right and left lasts, are made at the same time from the one pattern.

The gear 51 is driven by means of a pulley 54 mounted on the shaft 55 to which 40 the gear 51 is secured, and a belt 56 and pulley 57 are rotated by the shaft 58 which has the gear 59 in mesh with the gear 60, which, as will be seen from Figure 5, is not connected with the chuck casing and therefore is independently rotatable, since the 45 chuck casing has a stud or stud end supporting it in the bearing 37. The gear 60 and its shaft are supported by the bearing 60^a. The gear 60 is driven from the friction pulley 61, which has a small driving friction pulley 62 normally retreated by the screw 63 and being driven by a pulley 64^a and a belt 64 which, as will be seen from Figure 2, is operated from the pulley 55 65 on the same shaft with the worm gear 66 operated from the worm 67 on the jack shaft 47. The screws 41 and 63 are simultaneously operated, since they each have a disk 68, shown in Figure 8, rotatable by 60 means of a pin 69 in the stem 70, which stem 70 is normally held upward by a spring 71 and which is operated downwardly by means of the pedal 72, so that 65 when the pedal is pushed down the disks 68 are turned far enough to cause the

screws 41 and 63 to push the driving friction pulleys against the friction pulleys 38 and 61 and initiate not only the slow turning or rotating of the chucks, but also the revolving of the chucks themselves in their supports; in other words, holding the pattern and the lasts in the rotating chucks and revolving such rotating chucks on axis perpendicular to the axis of the chucks.

The chucks can be of different forms, but 75 I illustrate in Figures 10-13, inclusive, a chuck in detail having two slidable members 73 and 74 which are slotted so as to fit one within the other, the slotted portions having bolts 75 passing through them, and 80 the nuts 76 form means for securing them in adjusted position.

The toe-engaging elements 77 and 78 are adjustable toward and from each other, the screws 79 and 80 being used to clamp them 85 in adjusted position. At the heel portion the step 81 supports the bottom of the last, and the bar 82 can swing to the open position shown in dotted outline in Figure 10, or when swung inward can be caught under 90 the hook 83, this being permitted on account of its pivotal connection 84, and a screw 85 mounted in the bar 82 carries the foot 86 which is pressed down tightly against the last to hold it in position. The shelf 87 95 is provided with a plate 88, shown in detail in Figure 13, which can be adjusted by reason of the slots 89 and which has its end 90 arranged to come opposite the end 99 of the last when the last is in its proper position, and being adapted to be swung up out of the way, as shown in dotted outline in Figure 12.

In the operation of the machine, when 105 a particular size and style of pattern and a particular size and style of last are to be used, the lasts 91 are placed as shown in Figure 6, that is, they are placed in the chucks and the chucks are adjusted so that they tightly receive each of the lasts, but 110 at the same time the frames 13 are advanced so as to receive the knobs 92 at the toe ends of the lasts on the centering screws 93 of the frame, and the ribs 94 left on lasts coming from the lathe are arranged in the 115 tail pieces 95 on the opposite frame 13, all the lasts being thus assured of the same position, that is, they are aligned vertically and horizontally, and the plate 88 on each chuck is in position where it rests with 120 its top end at the end of the last proper. The frames 13 are then moved back and the block or support 34 for the chucks, being easily swung, is slightly turned and the center last is taken out and a pattern 125 is inserted, this pattern having its ends finished and being without these front and rear rough projections, such pattern being shown in the center chuck in Figure 5. The center last is the one against which the 130

pattern wheels 19 bear, the gates 18 being yieldingly held against the work by suitable means such as the weights 96 suspended by cords 96^a passing over pulleys 96^b. This adjustment, of course, is only necessary when a new style or size of last is to be finished.

Figures 2 and 3 show the position of the parts after this adjustment has been completed, and the frames 13 are slightly retreated. The pedal 72 is then pushed down, which forces the driving friction pulleys 62 and 39 so that they engage the friction pulleys 38 and 61, and the chucks then begin to slowly rotate in the direction of the arrows shown in Figures 3 and 4, presenting the ends of the article, such as the last 91, to the action of the cutters, the swinging of the work forcing the cutters outward, as will be seen from Figure 4. While this is going on, each last and the pattern are being revolved within the chuck by reason of the mechanism heretofore described, embracing the gears 59 and 60 and their connection with the gears 49, 50 and 53 of the chucks, so that the lasts are twisted while they are revolving with the chuck, thereby thoroughly finishing both ends and over their complete surface.

When the operation is complete, the latches 33 hold the gates apart, the chuck support 34 is partly turned back to or slightly beyond its original position, the finished lasts in the top and bottom chucks are removed by unscrewing the screw 85, and since the bed has been made on the original last, all that has to be done is to push in the last until the plate 88 indicates how far it should be pushed in, the toe end being held by its clamping elements, again screw the screw 85 down and another pair of lasts can be finished by again starting the machine. During this removal and insertion of successive lasts it is not necessary to readjust the frames 13.

In case, however, that a different form or a different size of last is to be finished, a readjustment of the chucks, of course, is necessary, and in this case, to avoid injury, it is desirable that the frames be retreated or pushed back as shown in Figure 1.

It will be evident that minor changes can be made in the arrangement of the parts without departing from the scope of the invention.

I claim:

1. A machine for finishing the ends of turned articles comprising a rotatable chuck

support, a set of chucks rotatable in the chuck support on an axis perpendicular to the axis of the rotation of the support and adapted to hold the articles and a pattern with their ends exposed, yieldingly swinging gates having cutters and a tracer to engage the ends of the articles, means for rotating the chuck support and means for rotating the chucks in the support.

2. A machine for finishing the ends of turned articles comprising a rotatable chuck support, a set of chucks rotatable in the chuck support on an axis perpendicular to the axis of the rotation of the support and adapted to hold the articles and a pattern with their ends exposed, yieldingly swinging gates having cutters and a tracer to engage the ends of the articles, means for rotating the chuck support and means for rotating the chucks in the support said last mentioned means being disposed to rotate one of the articles in a direction the reverse of that of the pattern and the other article.

3. A machine for finishing the ends of turned articles comprising a rotatable chuck, means for rotating the support, a set of chucks rotatable in the support on axes perpendicular to the axis of rotation of the support, means for rotating the chucks, a pair of opposed frames slidable toward and from the support, and having means for engaging the ends of the articles in chucks so as to align them, gates arranged to swing on the frames and projecting beyond said aligning means, and cutters and a pattern secured on the gates, and means for operating the cutters.

4. A machine for finishing the ends of turned articles comprising a rotatable chuck, means for rotating the support, a set of chucks rotatable in the support on axes perpendicular to the axis of rotation of the support, means for rotating the chucks, a pair of opposed frames slidable toward and from the support, and having means for engaging the ends of the articles in chucks so as to align them, gates arranged to swing on the frames and projecting beyond said aligning means, and cutters and a pattern secured on the gates, means for operating the cutters and means for securing the frames in adjusted positions.

In testimony that I claim the foregoing, I have hereto set my hand, this 10th day of June, 1922.

GEORGE W. DUCHEMIN.
